CABINET FOR A PRINTING MACHINE

Richard H. Zornow, Manhattan Beach, Calif., assignor to
Hughes Aircraft Company, Culver City, Calif., a corporation of Delaware

Application March 26, 1954, Serial No. 29,713

Term of patent 14 years

(Cl. D64—11)

FIG. 1.

FIG. 2.

FIG. 3.

To all whom it may concern:

Be it known that I, Richard H. Zornow, a citizen of the United States of America and residing at Manhattan Beach, in the county of Los Angeles and State of California, have invented a new, original, and ornamental Design for a Cabinet for a Printing Machine, of which the following is a specification, reference being had to the accompanying drawings, forming part thereof.

Fig. 1 is a front isometric view of a cabinet for a printing machine, showing the new design;

Fig. 2 is a side elevation of the cabinet as seen from the right side; and

Fig. 3 is a plan view of the cabinet.

I claim:

The ornamental design for a cabinet for a printing machine, substantially as shown.
